United States Patent Office

Des. 185,904
Patented Aug. 18, 1959

185,904

SHAVER

Raymond A. Somers, Fairfield, Conn., assignor to Sperry Rand Corporation, New York, N.Y., a corporation of Delaware

Application January 5, 1959, Serial No. 54,037

Term of patent 14 years

(Cl. D22—3)

FIG. 2

FIG. 4

FIG. 1

FIG. 5

FIG. 3

Fig. 1 is a front elevational view of a shaver showing my new design, the side opposite thereto being similar in appearance;

Fig. 2 is a top plan view thereof;

Fig. 3 is a bottom plan view;

Fig. 4 is a side elevational view as seen from the left of Fig. 1; and

Fig. 5 is a side elevational view as seen from the right of Fig. 1.

The essential features of the design reside in the portions shown in solid lines on the drawing.

I claim:

The ornamental design for a shaver, substantially as shown and described.
